UNITED STATES PATENT OFFICE.

ROSS B. WALMER, OF MILLBANK, SOUTH DAKOTA.

STEERING ATTACHMENT FOR HARVESTERS.

SPECIFICATION forming part of Letters Patent No. 436,198, dated September 9, 1890.

Application filed June 18, 1890. Serial No. 355,876. (No model.)

To all whom it may concern:

Be it known that I, ROSS B. WALMER, of Millbank, in the county of Grant, in the State of South Dakota, have invented a new and 5 useful Improvement in Steering Attachments for Harvesters, of which the following is a specification.

My invention consists in a new and improved steering or guiding attachment for 10 harvesters, which will be hereinafter fully described and claimed.

Referring to the accompanying drawings, Figure 1 is a side view of my improvement. Fig. 2 is a longitudinal section of the same. 15 Fig. 3 is a top plan view of the same with the seat removed. Fig. 4 is a detail bottom plan view of Fig. 3, and Figs. 5 and 6 are detail views.

The same numerals of reference indicate 20 corresponding parts in all the figures.

Referring to the several parts by their designating-numerals, 1 indicates the header beam or tongue of a header or harvester, to which my invention is shown attached in 25 operative position. Upon this tongue is secured at the point shown a circular bearing-plate 2, which is formed with an annular groove 3 near its outer edge and a circular central recess 4.

30 5 indicates a circular wooden platform, upon the lower side of which is secured concentrically a circular metal casting 6, having the downwardly-extending edge flange 7, the lower edge of which fits and turns in the annular groove 3 of the plate 2, and being formed with a central downwardly-extending collar 8, the lower end of which fits in the central recess 4 of the bearing-plate.

To the underside of the platform is secured, 40 eccentrically, a metal ring 9, formed with an outwardly-extending flange 10 at its lower edge. This ring may be called the "eccentric-ring," as it is secured eccentrically to the wooden platform. The platform is secured 45 on the bearing-plate by a long central king-bolt 11, which passes down through the platform, the casting 6, the bearing-plate 2, and the tongue 1, as shown.

The flanged eccentric-ring 9 is encircled 50 loosely by a flanged metal ring 12, having a socket 13 at one side, in which is bolted one

end of a lever 14. The outer end of this lever is provided with a vertical metal bearing 15, in which fits and turns the round stem 17 of a bearing-block 16.

At the end of the tongue 1 is the guide-wheel 18, the round shaft 19 of which passes up through a bearing in the tongue and has its upper extremity flattened. 20 indicates a short round connecting-rod, which passes loosely through and slides in the opening of the bearing-block 16, and is formed near its outer end with a squared opening 21, through which the squared upper end of the wheel-shaft 19 passes. Upon the top of the tongue 65 is formed a circular recess 22, in which a circular bearing-plate 23 is secured, this bearing-plate being formed with an annular groove 24 in its upper side.

25 indicates a flat casting, which is secured upon the plate 23 by a central pivot-bolt 26, and which has a collar 27 on its lower side, which fits and turns in the annular groove 24 of the bearing-plate. Upon each end of the casting 25 is pivoted an anti-friction roller 28, 70 having a flange 29 at its lower end, and the lever 14 passes between these rollers and rests upon their lower end flanges, thus greatly reducing friction. Upon the upper side of the platform 5 are secured the series of "steps" 75 31 indicates a spring-seat secured upon the tongue at the point shown.

In operation the driver sits upon the seat 80 31, with his feet resting upon the platform, and when he wishes to turn to the right or left steers or guides the harvester by pressing with his feet against the foot-bars 30. It will be seen that when the platform 5 is turned in either direction by pressing with the feet 85 against the bars 30 the eccentric 9 on the lower side of the platform, turning in the lever-ring 12, will slide the lever 14 backward and at the same time to the side, as shown in the drawings, according to the direction in 90 which the platform 5 is turned, thus through the connecting-rod 20 turning the guide-wheel 18 around to either side, as will be clearly seen. The lever slides back and forth between the anti-friction rollers 28 of the casting 95 25, the casting turning on its central pivot to prevent binding.

From the foregoing description, taken in connection with the accompanying drawings, the construction, operation, and advantages of my invention will be readily understood.

5 It will be seen that the driver can sit down and steer or guide perfectly with his feet, and that my attachment can be applied to any header or harvester.

Having thus described my invention, what 10 I claim, and desire to secure by Letters Patent, is—

1. The combination, with the tongue of a harvester and the seat 31 secured upon the same, of the circular platform centrally pivoted upon the tongue, having the foot-bars upon its upper side and the flanged eccentric upon its lower side, the ring 12, encircling the eccentric and having the side socket 13, the lever 14, having the vertical bearing 15 at its outer end, a bearing 25, in which the said lever slides, the bearing-block 16, having the round stem 17, the guide-wheel having the squared upper shaft end, and the connecting-rod 20, substantially as set forth.

2. The combination, with the tongue of a harvester and the seat 31 secured upon the same, of the bearing-plate 2, formed with the annular groove 3 and central recess 4, the platform having the foot-bars and the flanged eccentric upon its lower side, the casting 6, having the edge flange 7 and central collar 8, the king-bolt 11, the ring 12, having the side socket 13, the lever 14, having the vertical bearing 15 at its outer end, a bearing 25, in which the said lever slides, the bearing-block 16, having the round stem 17, the guide-wheel

having the squared upper shaft end, and the connecting-rod 20, substantially as set forth.

3. The combination, with the tongue of a harvester and the seat 31 secured upon the same, of the circular platform centrally pivoted upon the tongue, having the foot-bars and the flanged eccentric upon its lower side, the ring 12, having the side socket 13, the centrally-pivoted casting 25, having pivoted at its ends the anti-friction rollers 28, having the flanged lower ends, the lever 14, having the vertical bearing 15 at its outer end, the bearing-block 16, having the round stem 17, the guide-wheel having the squared upper shaft end, and the connecting-rod 20, substantially as set forth.

4. The combination, with the tongue of a harvester and the seat 31 secured upon the same, of the platform centrally pivoted upon the tongue, having the foot-bars and the flanged eccentric upon its lower side, the ring 12, having the side socket 13, the bearing-plate 23, formed with the annular groove 24, the centrally-pivoted casting 25, having the collar 27 on its lower side, the anti-friction rollers 28, having the flanged lower ends and pivoted on the ends of casting 25, the lever 14, having the vertical end bearing 15, the bearing-block 16, having the round stem 17, the guide-wheel having the squared upper shaft end, and the connecting-rod 20, substantially as set forth.

ROSS B. WALMER.
